UNITED STATES PATENT OFFICE.

WILLIAM L. McGOWAN, OF GALT, MISSOURI.

IRONING BOARD.

Application filed March 19, 1920. Serial No. 367,067.

To all whom it may concern:

Be it known that I, WILLIAM L. McGOWAN, a citizen of the United States, residing at Galt, in the county of Grundy, 5 State of Missouri, have invented a new and useful Ironing Board; and I do hereby declare the following to be a full, clear, and exact description of the invention, such as will enable others skilled in the art to which 10 it appertains to make and use the same.

The invention relates to ironing boards and has for its object to provide an ironing board, which ironing board is pivotally secured in a casing, which casing is adapted 15 to be set into a wall thereby forming a convenient storage place for the ironing board so that the ironing board at all times when not in use will be out of the way.

A further object is to provide an ironing 20 board cabinet adapted to be imbedded in a wall, and to provide a vertically slidable and adjustable frame in said cabinet, to which frame at its lower end, one end of the ironing board is pivotally connected in such a 25 manner that said ironing board may be folded upwardly into the cabinet when the slidable frame is in a lowered position. Also to provide means carried by the frame for holding the ironing board in a horizontal 30 position when in use.

With the above and other objects in view the invention resides in the combination and arrangement of parts as hereinafter set forth, shown in the drawings, described and 35 claimed, it being understood that changes in the precise embodiment of the invention may be made within the scope of what is claimed without departing from the spirit of the invention.

40 In the drawings:—

Figure 1 is a perspective view of the ironing board cabinet showing the ironing board in position for use.

Figure 2 is a detail sectional view through 45 the vertically adjustable frame and a portion of the ironing board.

Figure 3 is a detail sectional view taken on line 3—3 of Figure 1.

Figure 4 is an enlarged detail sectional 50 view through the lower portion of the cabinet, showing the slidable frame removed.

Figure 5 is a detail view showing the means for securing the weight cords to the 55 slidable frame.

Referring to the drawings, the numeral 1 designates a rectangular shaped cabinet

which is adapted to be imbedded in a wall and 2 a flange around the opening 3 of the cabinet, which flange engages the surface of the wall when the cabinet is in place. Slid- 60 ably mounted on guide strips 4 carried on the inner faces of the sides 5 of the cabinet is a rectangular-shaped frame 6. The frame 6 is provided with channels 7 for the reception of the guide strips 4 so that said frame 65 will be held within the chamber of the cabinet as the same is moved upwardly and downwardly. However to assist and counterbalance the frame 6 conventional form of weights 8 may be utilized, which weights 70 are connected to the frame 6 as at 9 by means of cords 10, said cords 10 passing upwardly and over conventional forms of pulleys 11. The frame 6 comprises side rails 12, which rails are connected together 75 by cross bars 13, 14, and 15. Hingedly connected to the cross bar 15 as at 16 is an ironing board 17, the rear end of said ironing board projecting rearwardly of the bar 15 so that when said board 80 is in a horizontal position its end 18 will engage the cross bar 14 and be limited in its downward movement. The cross bars 13 and 14 are so positioned that when the board 17 is moved upwardly so that 85 it will be housed in the cabinet 1, said bars 13 and 14 will limit the inward movement of the board. In Figure 2 and also in Figure 1, the board is shown in vertical position in dotted lines. When the board 17 90 is in vertical position, pins 19 are placed in apertures 20 in the rails 12 of the frame 6 for holding the board in said vertical position. The rails 12 are also provided with apertures 21, which apertures are adapted 95 to be placed in registration with any of the apertures 22 in the side 5 of the cabinet, so that pins 23 may be passed through said registering aperture for holding the frame 6 in any position to which it may have been 100 moved.

The cabinet is preferably provided with a door, however for purposes of illustration the door has been eliminated so as to more clearly show the structure.

When it is desired to use the ironing board, the pins 19 are removed, then the operator grasps the upper end of the ironing board 17 and pulls outwardly on the same until the board resumes the position shown 110 in Figure 2, at which time the operator adjusts the frame 6 upwardly to the desired

height for ironing and places the pins 23 through the registering apertures 21 and 22 so that the frame will be held in adjusted position. When it is desired to fold the ironing board back into the cabinet the above operation is reversed.

The invention having been set forth what is claimed as new and useful is:—

10 A vertically slideable supporting member for supporting and holding an ironing board in a horizontal position and in a vertical position, said supporting member comprising a frame having spaced parallel side rails, a transversely disposed horizontal bar carried adjacent the lower ends of the parallel side rails and adjacent their front sides, an ironing board hingedly connected to said horizontal bar, a second horizontal bar connecting the rear sides of the parallel side rails parallel to and spaced above and rear-

wardly of the first mentioned horizontal bar a distance substantially equal to the thickness of the ironing board, a bar connecting the rear sides of the parallel side rails and located in vertical alignment with 25 the other connecting bar carried by the rear side of the parallel side rails, a removable pin carried adjacent the upper end of one of the bars and spaced from the adjacent horizontal bar a distance substantially equal to 30 the thickness of the ironing board, and means to hold said supporting member in fixed position.

In testimony whereof I have signed my name to this specification in the presence 35 of two subscribing witnesses.

WILLIAM L. McGOWAN.
